MOP CONNECTER

Harry Hertzberg, New York, N. Y.

Application July 26, 1934, Serial No. 736,987

4 Claims. (Cl. 306—20)

This invention relates generally to mop heads and more particularly to an improved form of means for pivotally connecting a mop head to a handle therefor.

5 It is the object of this invention to provide a holder for a mop head which consists of a single piece of metal adapted for attachment to a mop handle at its rear portion and provided at its front end with a tubular part for securely and adjustably holding the pivot bar of a mop head.

10 It is another object of this invention to provide separate means on the tubular part of the mop holder for clamping the pivot bar to insure a definite angular position of the mop head to the handle axis.

15 These and other objects and advantages of the invention will be apparent from the description thereof to follow taken in connection with the accompanying drawing in which—

20 Figure 1 is a plan view of a mop embodying the invention.

Figure 2 is a side elevation of the lower end of the mop handle and mop holder attached thereto, partly in section on the line 2—2 of Figure 1.

25 Figure 3 is a plan view of the mop holder shown in Figure 1 having the sheepskin protector in opened position.

30 Figure 4 is a side elevation of Figure 3 showing the mop holder with sheepskin protector fully attached thereto and the pivot bar clamped therein.

35 Referring to the drawing, Figure 1 shows a floor mop comprising a mop head consisting of mopping material 10 intertwined between wires 11 which are formed into a loop and provided with a straight portion 11a forming a pivot bar adapted to be held and clamped in the journal part 21 of the mop holder 20. The mop holder 20 is preferably stamped and formed of a single 40 piece of sheet metal and consists of a tubular cylindrical rear portion 22 adapted to surround the lower end of a mop handle 12 and provided with two outwardly extending parallel flanges 23 which may be drawn towards each other by

45 a small carriage bolt 24 having its square portion lodged in a corresponding aperture of one of said flanges, and a wing nut 25 pressing against the outer face of the other flange. The middle portion 20 of the mop holder consists of the flat plate 50 portion 20a which widens out towards the front of the holder and a conical portion 20b between said plate portions which tapers to a point towards the front of the holder. The front end of the mop holder consists of the tubular portion 55 21 arranged transversely to the axis of the holder

into which the pivot bar 11a is inserted. This portion 21 is formed by bending the sheet metal plate upward in front of the point of the taper portion 20b and rearward above the same to form the clamping plate 26 extending rearward above the front part of the taper portion 20b. Clamping plate 26 is provided with a small aperture to accommodate the clamping carriage bolt 27 which also extends through a square aperture in the tapered portion 20b, in which the square part 27a of the bolt is lodged. To arrange bolt 27 perpendicularly to the normal direction of clamping plate 26 the sheet metal of plate 26 surrounding the bolt 27 and its head is indented by deforming the tapered portion 20b at 20c so that at 10 that point it is parallel to clamping plate 26 and the head of bolt 27 is concealed within the recess of the tapered portion 20b so formed, as shown in Figure 2. Outside of clamping plate 26, bolt 27 carries a hexagon nut 28 for drawing plate 26 15 towards 20c and thereby contracting cylindrical portion 21 and clamping pivot bar 11a therein. It has been found through experiment however that no secure clamping of the pivot bar can be effected in that manner because the cylindrical 20 portion of sufficiently stiff sheet metal does not provide sufficient resiliency for clamping purposes and permits an unwanted rotation of the pivot bar within its cylindrical holder. To avoid this disadjustment, plate 26 is provided in front 25 of nut 28 with a resilient tongue 30 preferably formed integral with plate 26 by cutting a V shaped slot 31 therein and bending the metal enclosed by said slot in a slightly downward inclined direction as shown in Figures 2, 3 and 4. 35 The spring so formed impinges upon pivot bar 11a in tightening nut 28 long before the cylindrical portion 21 starts any binding action and when the pivot bar 11a is clamped the tongue 30 securely holds that bar and prevents disadjustment of 40 the angular position of the mop head in case of looseness of the pivot bar 11a in the cylindrical portion 21.

45 To prevent injury to furniture or other articles in mopping floors by the metal parts of this mop holder, the front parts of the holder are covered by an elongated piece of sheepskin 32 with the fleece thereon, or other compressible resilient material which is provided with apertures 33 at opposite ends. This sheepskin 50 covering is folded over the cylindrical portion 21, plate 26 and the front part of the conical portion 20b. One end of the covering is placed under the head of bolt 27 which passes through one of its apertures to be pressed against part 55

26a and the other end is passed over the point of the same bolt to lean against plate 26 and pressed against this plate by nut 28.

I desire to make it understood that changes 5 in the details of this invention may be made without departing from the principle thereof and I wish to be limited only by the state of the prior art and the appended claims.

I claim:

- 10 1. A handle connector for pivotally fastening a mop to a handle consisting of a tubular rear portion having parallel flanges thereon for contracting said tubular portion, a journal at the front end of said connector transversely to said tubular portion, a clamping plate extending from said journal, a pivot bar in said journal, a middle portion connecting said journal integrally with said tubular portion, clamping means extending through said clamping plate and said 20 middle portion for contracting said journal and a resilient member formed integrally with the clamping plate extending into said journal to engage said pivot bar when said journal is being contracted by said clamping means.
- 25 2. A handle connector for mops comprising a split tubular member adapted to detachably engage the mop handle, an extension on said tubular member formed integrally therewith and terminating in a loop at its outermost end for receiving a portion of the frame of the mop head and a tongue member formed integrally on said

turned portion and adapted to engage the frame portion to prevent turning of said frame portion in the loop.

3. A handle connector for mops including a split tubular member adapted to detachably engage one end of the mop handle, an integral extension formed on said tubular member, said extension terminating in a loop portion at its outermost end for receiving a portion of the wire frame of the mop head, a V-shaped tongue member formed integrally on said extension and projecting into the loop to engage the wire frame and a bolt and nut connection between the outward and inward portions of the extension for pressing said tongue member against said wire 10 frame.

4. A handle connector for mops including a split tubular member adapted to detachably engage one end of the mop handle, an integral extension formed on said tubular member, said extension terminating in a loop portion at its outermost end to receive a portion of the wire frame of the mop head, a tongue member formed integrally on the extension and adapted to engage the wire frame, a protecting cover around 20 said looped portion and tongue member and a bolt passing through said extension and cover to hold the cover on the looped portion and tongue member.

HARRY HERTZBERG. 30
